BINGO GAME APPARATUS

James S. Hofsetz, Denver, Colo.

Application May 2, 1949, Serial No. 90,933

5 Claims. (Cl. 200—5)

1

This invention relates to a game device for use in playing the well-known game of "bingo," and has for its principal object the provision of a highly efficient mechanism which will constantly and effectively agitate and intermix the numbered balls employed in such a game; which will deliver these balls to the operator in a chance sequence; and which will provide a rack for receiving the delivered balls, insertion of the ball in which will act to close an indicating circuit.

Another object of the invention is to provide a ball-receiving rack for "bingo" games in which the delivered balls will be supported in their proper numerical positions until the game is completed; and which will discharge all of the balls from the rack simultaneously upon completion of the game.

A further object is to so construct the ball discharge mechanism of the rack that it will operate to open all indicating electrical circuits of the machine when the balls are discharged from the rack.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in views of the drawing and throughout the description.

In the drawing:

Fig. 1 is a plan view of the improved game device;

Fig. 2 is a rear view thereof;

Fig. 3 is a front view thereof;

Fig. 4 is an enlarged cross-section, taken on the line 4—4, Fig. 3;

Fig. 5 is an enlarged detail section taken on the line 5—5, Fig. 4;

Fig. 6 is a face view of an illuminated number indicating board employed with the improved game device; and

Fig. 7 is a circuit diagram illustrating the circuits employed between the device and the indicating board of Fig. 6.

The improved game device is built into a desk-like structure supported upon suitable legs 19 and consisting of a ball compartment 11 and a rack compartment, designated in its entirety by the numeral 12.

The ball compartment is closed at the top by means of a transparent cover 13, and is provided with a window 14 in the front, through which the

2

game balls, indicated at 15, are visible. A hopper-like sub-bottom 16 is positioned in the ball compartment 11. The central portion of the sub-bottom 16 is formed by a horizontal rotating disc 17 mounted on the shaft of a motor-turning device 18 so that it will rotate at approximately 150 revolutions per minute. The disc 17 carries a diametrically positioned scattering vane 19 which acts to agitate and intermix the pile of balls resting on the sub-bottom 16 and the disc 17.

A ball-discharge tube 20 leads through the wall of the sub-bottom 16 to a ball delivery trough 21 projecting from the rear face of the ball compartment 11. The balls enter the ball compartment 11 through a receiving opening 22 formed in the inside wall of the ball compartment 11. The balls are fed to the opening 22 by means of an inclined bottom 23 which extends throughout the entire area of the rack compartment 12.

An inclined rackboard 24 covers the top of the rack compartment 12 and is supported on cleats 46, see Fig. 5. The plate 24 is provided with a plurality of ball-receiving holes 25 arranged in laterally and longitudinally extending rows. Each hole is numbered, as indicated at 45, to correspond to a number on one of the balls 15.

In the usual "bingo" game there are seventy-five balls, and the rack board 24 would be provided with seventy-five of the ball holes 25 arranged in five longitudinal rows of fifteen holes per row. For convenience of illustration, only thirty-five holes are illustrated, arranged in five rows of seven holes each. It is to be understood the number of rows and holes can be varied according to demands of the particular game.

A shifting plate 26 is mounted beneath and against the rackboard 24 and is provided with ball openings 27 similar in size and spacing to the holes 25. The shifting plate 26 is slidably mounted in the cleats 46 so that it may be shifted forward and back. When the shifting plate is in its forward position, indicated in Fig. 4, the openings 27 are slightly out of alignment with the holes 25 so that a ball cannot fall through the openings 27 but is supported by the plate 26, as shown in Fig. 4. When the shifting plate is moved rearwardly, the openings 25 and 27 align with each other, allowing the balls to fall through onto the inclined bottom 23, thence through the opening 22 to the ball compartment 11. An inclined window 47 is provided in the front of the device through which the returning balls are visible to the players.

The plate 26 is shifted from a rotatable lever 65 shaft 28 through the medium of levers 29 which

are affixed to and project from the shaft 28 and which are connected to the plate 26 by means of suitable connecting links 30. The shaft 28 is rotated by means of handles 31 extending to the operator's position at the rear of the machine.

A switch board 32 is supported below the shifting plate 26 in parallel relation thereto. This board is also provided with ball openings 33 positioned in alignment with the openings 25. The switch plate carries a plurality of toggle switches 34, the handles of which, indicated at 35, extend upwardly through handle slots 36 in the rack board 24 to a position above the latter. Each of the slots 36 joins one of the holes 25 so that the handles 35 may be swung to a position to partially project over the holes 25 when the switches are in the "off" position. When in the "on" position, the handle extends forwardly in the slot 36.

The holes 27 in the shifting plate are also provided with notches for the passage of the handles 35. The latter notches are so arranged that when the plate 26 is shifted rearwardly to align the openings 27 and 25, the extremities of the notches will engage the switch handles 35 which are in the "on" position and force them rearwardly simultaneously to the "off" position.

Each of the switches 34 is connected by means of a conductor 37 to a signal lamp 38. All of the lamps 38 are grounded by means of a ground wire 39 to a source of power 40, and all of the switches 34 are connected to the source of power 40 by means of a main conductor 41. The lamps are positioned behind a translucent face plate 42 in a light box 43. The face plate 42 is divided into sections and the sections carry numerals 44 corresponding in number and arrangement to the numerals 45 on the rack board 24.

Let us assume that all of the balls are in the ball compartment, and that they are being stirred and intermixed by means of the rotating disc 17 and the scattering vane 19. Certain of the balls will roll into the ball discharge tube 20, and from thence into the trough 21. The operator will pick up the foremost ball in the trough and call the number thereof to the players, and will then place the selected ball in its proper receiving opening 25. As the ball is placed in its receiving opening, the switch handle of that opening is forced forwardly to admit the ball and to turn the toggle switch 34 of that opening to the "on" position. This closes one of the circuits 37 and illuminates the number on the face plate 42 corresponding to the number of that particular ball.

This procedure is continued until a player completes a prescribed row of numbers as is usual in the game of "bingo." The winning numbers are checked back with the operator and if correct the handles 31 are depressed, causing the shifting plate 26 to move rearwardly so as to align its openings 27 with the openings 25 of the plate 24. This allows all of the balls to drop to the inclined bottom plate 23 to be returned by gravity to the ball compartment 11. The rearward movement of the shifting plate 26 simultaneously throws all of the "on" switches 34 to the "off" position, thus extinguishing all of the lamps 38 so that the device will be set up ready for the next game.

While a specific form of the improvement has been described and illustrated herein, it is to be understood that the same may be varied, within the scope of the appended claims, without departing from the spirit of the invention.

Having thus described the invention, what is claimed and desired secured by Letters Patent is:

1. Electric switching means for a game apparatus of the type having a substantially horizontal rack board provided with a plurality of ball passages extending therethrough and having a shifting plate slidably positioned below said rack board and provided with a similar number of corresponding passages, comprising a switch board positioned below said shifting plate and provided with openings corresponding to the passages in said rack board; a plurality of toggle switches mounted on said switch board, there being one switch for each opening therein; and a switch-operating handle extending upwardly from each toggle switch through both said rack board and said shifting plate so as to be operable from above the former.

2. Electric switching means for a game apparatus of the type having a substantially horizontal rack board provided with a plurality of ball passages extending therethrough and having a shifting plate slidably positioned below said rack board and provided with a similar number of corresponding passages, comprising a switch board positioned below said shifting plate and provided with openings corresponding to the passages in said rack board; a plurality of toggle switches mounted on said switch board, there being one switch for each opening therein; a switch-operating handle extending upwardly from each toggle switch through both said rack board and said shifting plate so as to be operable from above the former, the openings in said shifting plate being so arranged in relation to said switch handles that the latter will be forced to the "off" position when the openings in the shifting plate are shifted into alignment with the passages in the rack board.

3. Electric switching means for a game apparatus of the type having a substantially horizontal rack board provided with a plurality of ball passages extending therethrough and having a shifting plate slidably positioned below said rack board and provided with a similar number of corresponding passages, comprising a switch board positioned below said shifting plate and provided with openings corresponding to the passages in said rack board; a plurality of toggle switches mounted on said switch board, there being one switch for each opening therein; a switch-operating handle extending upwardly from each toggle switch through both said rack board and said shifting plate so as to be operable from above the former, the openings in said shifting plate being so arranged in relation to said switch handles that the latter will be forced to the "off" position when the openings in the shifting plate are shifted into alignment with the passages in the rack board; a lever shaft extending along said shifting plate in parallel relation to the rear edge of the latter; levers projecting from said lever shaft; means connecting said levers to said shifting plate; and manual handles mounted on said shaft for rotat-

ing the latter to reciprocate said shifting plate.

4. A rackboard and switch apparatus for bingo games comprising: a stationary rackboard having a plurality of ball holes; a shifting plate slidably mounted below said rackboard and having openings positioned to register with the holes in the rackboard; a switch-supporting member positioned below said shifting plate; a plurality of switches mounted on said switch-supporting member, there being one switch for each open-

ing in the shifting plate; a switch-operating handle for each switch, said handles projecting upwardly through the shifting plate and through the rack board adjacent the holes therein, said switches and handles being so positioned that when in the "off" position, said handles will extend into said holes to prevent a ball from entering, and when in the "on" position, said handles will be swung to one side of said holes to allow the balls to enter therethrough.

5. A rackboard and switch apparatus for bingo games as described in claim 4 in which the switch-operating handles are placed to be contacted by said shifting plate as the latter moves to align its openings with the holes in said rack board to simultaneously swing all of said handles to the "off" position. 15
